CASE OR CONTAINER FOR CIGARETTES AND
LIKE ARTICLESJohn Edward Harris Morgan and Victor John
Forsythe Donnelly, London, EnglandApplication June 21, 1937, Serial No. 149,516
In Great Britain December 8, 1936

6 Claims. (CL. 206—41.4)

This invention relates to cases or containers, for cigarettes and like articles furnished with a chamber capable of containing a number of such articles which are to be extracted singly or one by one.

The chief object of the invention is to provide reliable, efficient and easily operated means, whereby a single article is automatically, partially extracted or protruded from the case, and presented in a position in which it can be gripped easily for complete removal.

A further object of the invention is to provide means whereby the operation of the necessary devices are controlled by a single hand operated device.

Another object of the invention is to provide for the ignition of one end of the partially extracted cigarettes when presented or protruded in an inclined position by the extractor.

Other objects of the invention will be referred to in the detailed description which follows and pointed out in the appended claims.

According to the present invention, the case or container is provided with a carrier or extractor adapted or contrived to receive and hold a single cigarette or like article, which is hinged or pivotally mounted at one end or side of the case or of the compartment and on the movement or actuation of the single hand operated control-device is given a swinging angular or rotary movement whereby a cigarette is partially extracted and one end thereof raised or moved into a position to be gripped or removed either by the lips or by the fingers.

According to the invention also, the said hand operated control-device, may also control a stop or barrier to prevent the ejection of cigarettes from the case when the extractor is moved and may also control a gripper for the cigarette, on or in the extractor.

Further in accordance with the invention, when a cigarette has been partially removed by the extractor, the lower end of the cigarette may be placed in close proximity to and lit before removed from the extractor by a lighter which may be arranged on or within the frame of the case or container.

The single hand-operated device which controls the extractor may also control the lighter in timed relation to the movement of the extractor.

By means of this invention a case or container is provided which may be held in one hand and the single controlling device operated by a finger of the same hand, to effect the ready presentation of a cigarette, for removal or for being lit and removed.

In accordance with the invention also the cigarettes or the like are pressed or fed towards the extractor or carrier by a feed device which

may be released for action by the closing of a movable side or end of the case or container.

The extractor or carrier can be returned to initial or closed position by hand or by the action of a finger whilst the case is held in the hand and when a lighter is provided the lid or cover thereof is so arranged that the act of closing this cover for the lighter or returning the operative part or parts thereof to initial position, such act also returns the carrier or extractor to initial position. This setting or resetting act can also be performed whilst the case is held in a hand of the user by the operation of a finger of that hand.

Referring to the accompanying drawings: 15

Fig. 1 is a side elevation of a case embodying the present invention.

Fig. 2 is a plan view of the case shown in Fig. 1.

Fig. 3 is a vertical section on the line 3—3 of Fig. 1, with the extractor closed. 20

Fig. 4 is a detail section showing parts in a different position from that shown in Fig. 3.

Fig. 5 is a side elevation of the same device, partly in section.

Fig. 6 is a sectional plan on the line 6—6 of Fig. 5, and 25

Fig. 7 is another sectional plan of the same case.

In the embodiment of the invention hereinafter described and as illustrated, a lighter is incorporated to be actuated in co-operation or combination with the cigarette extracting devices. 30

The body of the case or container A may be formed of a single pressing, moulding or casting, of any suitable material with any desired finish, 35 and may be shaped externally to facilitate holding in the hand. The body in this embodiment, is divided internally into a compartment or magazine A¹ for the cigarettes or the like and a compartment A² for the lighter mechanism. 40

The carrier or extractor B is pivotally mounted or hinged at A³ to a fixed bracket A⁴, and a stop or the hinge A³ is so arranged that the extractor B can only open to a position such as indicated in Fig. 1. 45

The extractor B is furnished with one or two side walls B³ and is open on its inner or under side to receive a cigarette from the chamber A¹.

The extractor B is normally held in its closed position (see Fig. 5) by a movable barrier catch C⁷ which engages a projection B⁴ on the extractor. 50

The gripper to receive or hold a single cigarette is mounted within or on the extractor, and, in this embodiment, comprises a plate or finger B¹ hinged to the extractor and normally pressed, by a light spring B² (see Figs. 1 and 5), towards one side wall B³ of the extractor which forms the other member of the gripper. 55

The hand operated control-device comprises a 60

push button or the like C against one end of which an arm of a lever C¹ pivoted at C² bears under the action of a spring C³. When the push button C is pressed some distance inward a projection 5 C⁴ on the lever C¹ engages an arm or lever C⁵ integral with or fixed to a spindle C⁶ and partially rotates the spindle to move the barrier-catch C⁷ fixed thereon out of engagement with the projection or the like B⁴ on the extractor B 10 (see Fig. 5) and allow the latter to open under the influence of an actuating spring B⁵.

When a cigarette is wanted, the first movement of the control device operates so that the catch thereon releases a cooperating catch member on 15 the gripper, allowing the movable member thereof to close on the cigarette before the said control member releases the cover or extractor in which the gripper is mounted.

When the barrier catch C⁷ has been moved as 20 above described it will overlap or intercept the movement of the cigarette lying next to the one now engaged by the gripper on the extractor (see Fig. 3) and as the parts are so designed that this interception takes place before the catch releases the projection B⁴ on the extractor it will 25 in conjunction with a fixed bridge piece A¹⁰ or part of the body prevent the egress of cigarettes from the case when the extractor has been raised which would otherwise take place under the action 30 of a spring-controlled feed device D which constantly tends to press the cigarettes in the case towards the extractor.

When moved to its inner position, the barrier catch C⁷ will be locked automatically by a pivotally mounted locking lever C⁸ (see Fig. 1) which acts upon a lug C¹⁰ on the barrier catch, under the action of a spring C⁹.

On the closing of the extractor B by hand, the 40 projection B⁴ will push the arm or lever C⁸ out of engagement with the lug C¹⁰ and the barrier catch C⁷ will be moved outwards and into engagement with the projection B⁴ by the action of a coil spring C¹¹. This barrier catch in moving outwards, will engage with the free end of 45 the pivoted member B¹ of the gripper on the extractor and push it into the position shown in Fig. 4, against the action of the spring B². An unobstructed passage will thus be afforded for a cigarette to pass freely from the magazine A¹ 50 into the gripper or the extractor under the pressure of the feed device D.

The feed mechanism comprises a plate or bar D to which is attached a slide D¹ adapted to move freely on a fixed rail or guide D² under the action 55 of pivoted links D³, D⁴, which are actuated by two coil springs D⁵, D⁶.

The slide D¹ is provided with a lug D⁷ (see Fig. 6) which will, when necessary, make contact with the free end of a buffer spring D⁸, the other 60 end of which is fixed to the case body A. The magazine portion A¹ of the case is provided with a lid or cover A⁵ which may be hinged to the case body A at A⁶ or elsewhere on the case body. This lid A⁵ is conveniently held closed by a catch A⁷.

65 A flap E may also be mounted on the hinge A⁶ and a coil spring E¹ causes it to open against the lid A⁵ when released. When the lid is opened to recharge the magazine A¹, the feed mechanism D can be retracted by hand. A catch strip E² 70 furnished with two catches E³ and E⁴ is slidably mounted on the case A by means of two flat-headed fixed studs E⁵ which pass through holes in the catch-strip (see Fig. 7) to allow a limited horizontal and/or vertical movements of the respective ends of the catch strip E². A spring E⁶

5 mounted on the case A forces the catch strip E² upwards and to the left (see Fig. 7). The slide D¹ is also provided with another lug D⁹ with which the catch E⁴ will engage automatically when the feed mechanism is pulled fully back by hand. In this latter position, the links D³ and D⁴ are closely folded together under the feed bar D. When the slide D¹ is moved back, the lug D⁹ makes contact with the sloping edge of the catch E⁴ thus forcing the catch strip E² horizontally to the right, thereby causing the catch E³ to disengage from the flap E and allow the latter to open, under the influence of the spring E¹. The catch E⁴ then engages with the lug D⁹, thus holding the feed mechanism out of action, 15 so that the magazine A¹ may be easily loaded.

The closing of the lid A⁵ will cause the flap E, if the latter be incorporated, to close and a lug E⁷ to push down one end of the catch strip E² thus disengaging the catch E⁴ from the lug D⁹ and thereby releasing the feed mechanism. When the lug D⁹ is disengaged from the catch E⁴, the catch strip E² will slide further to the left by virtue of the spring E⁶. The catch E³ will then hold the flap E so that, should the lid A⁵ 25 be thereafter opened, any cigarettes X contained in the magazine will be retained by the flap E and its fixed counterpart, a flange A⁸ which is embodied in the case A.

In the present embodiment of the invention a 30 lighter F is employed and is arranged to be operated by the control-device or press button, in timed relation with the movement of the extractor. The lighter shown is conveniently of a known pyrophoric type and comprises as hitherto, 35 a reservoir F¹ fitted within the compartment A², a filling screw F², a wick F³ and absorbent material F⁴, a flint F⁵ is pressed by a spring F⁶, an adjusting screw F⁷ and a serrated flint wheel F⁸. A lid F⁹ acted on by coil springs F¹⁰ can partially 40 rotate about a pivot F¹¹ and cause the flint wheel F⁸, on the same pivot to partially rotate in known manner. The lid F⁹ carries a spring-loaded extinguisher cap F¹² which covers and seals the outer end of the wick F³ when the said lid is 45 closed. The lid F⁹ is provided with a lug F¹³, which is adapted to engage with a catch C¹² formed on the outer end of the spring-actuated crank lever C¹, thereby holding the said lid closed.

When the press button or the like C is moved 50 a short distance inward the lug F¹³ on the lighter lid F⁹ will be released and the flint-wheel F⁸ will be partially rotated to ignite the lighter.

A further movement or a continuance of the 55 movement of the button C will operate the extractor in the manner already described. When the extractor B has been thus operated, the arrangement of the components is such that the flame F¹⁴ of the lighter is in suitable position for acting directly on the lower end of the cigarette 60 X¹ through an opening B⁶ in the end of the extractor B when the latter is open, as shown in Fig. 1.

When it is desired to operate the lighter F alone, 65 without involving a movement of the extractor, the button C is or would be pushed only to such extent that it releases the catch C⁴ of the lighter, the lever C⁵ remaining free from the projection C⁴ by reason of the clearance provided between them.

It is also possible to extract cigarettes in succession without necessarily operating the lighter in each movement of the button C as once the button has been operated beyond the lighter con- 75

trol catch it can be operated repeatedly as its movements will control the extractor only.

In accordance with the present invention also the lid F⁹ of the lighter is so shaped and arranged that in closing it will come into engagement with a suitably shaped part of the rear or lower end of the extractor B if the latter be open, and will, in so doing, push the said extractor into the closed position as shown in Fig. 5.

10 A removable plate A⁹ is preferably provided to allow of access to the components of the control and operating devices co-operating with the push button C.

15 The case or container above described is particularly intended for carrying in the pocket and provides an article which whilst being held in the hand, can be operated either to extract partially and light a cigarette, or to extract partially a cigarette, or to light a cigarette already extracted, 20 by the operation of a finger of the hand holding the case; further by another movement of the same finger, the extractor and lighter may be closed. The operations above described may be performed when the case or container is supported on any convenient form of base or stand 25 in place of being held in the hand.

What we claim is:

1. In a case for cigarettes and similar articles furnished with a chamber for holding a number 30 of such articles the combination of an extractor, a pivot adjacent the said chamber on which the extractor can turn angularly, an expandible gripper on the extractor adapted to receive a single article, a single hand-operated device acting to 35 secure and release the extractor, means actuated by the hand-controlled device for positively effecting the closing of the gripper in advance of the angular movement of the extractor, and a spring acting to raise the extractor and gripper 40 to partially extract a cigarette from the chamber and present it for easy removal.

2. In a case for cigarettes and similar articles furnished with a chamber for a number of such articles, the combination of an extractor, a pivot 45 adjacent the chamber on which the extractor can move angularly, an expandible gripper on the extractor, adapted to receive a single article, an actuating spring for raising the extractor and gripper by an angular movement and partially 50 extract a cigarette and present it in an inclined position for easy removal, a barrier for the body of cigarettes in the chamber, a single hand operated control device, and separate means on the said control device for effecting in succession the 55 closing of the gripper on to a cigarette, the interposition of the barrier between the gripper and the topmost free cigarette in the chamber and the release of the extractor pivotal movement by its actuating spring.

60 3. In a case for cigarettes and similar articles furnished with a chamber for a number of such articles, the combination of an extractor, a pivot adjacent said chamber on which the extractor can move angularly, an expandible gripper for a 65 single article mounted on the extractor, a spring constantly tending to raise the extractor and the gripper by an angular movement to partially extract a cigarette and present it in an inclined position for easy removal, a barrier stop for the 70 body of cigarettes in the chamber, a single hand-operated control device, separate means on the hand-operated device for effecting in succession

the closing of the gripper, the interposing of the barrier between the gripper and the leading free cigarette in the chamber, and the release of the extractor, an elevating device for the cigarettes in the chamber, and a spring-device acting on the elevating device to move the cigarette towards the gripper. 5

4. In a case for cigarettes and similar articles furnished with a chamber for a number of such articles, the combination of an extractor, a pivot 10 adjacent the chamber, whereon the extractor can turn angularly, an expandible gripper for a single cigarette on the extractor, a spring constantly tending to raise the extractor and the gripper by an angular movement to partially extract 15 a cigarette and present it in an inclined position for easy removal, a barrier stop for the body of cigarettes in the chamber, a single hand-operated control device, separate means on the hand operated device for effecting in succession 20 the positive closing of the gripper, the interposing of the barrier between the gripper and the leading cigarette in the chamber and the release of the extractor, an elevating bar for the body of cigarettes in the chamber, spring-controlled 25 arms acting on the elevating bar, a cover for the chamber, means for rendering the elevating bar temporarily inoperative, and means on the case cover for releasing the said last-mentioned means. 30

5. In a case for cigarettes and similar articles having a chamber for a number of such articles, the combination of an extractor a pivot for the extractor at one side of the chamber, a retaining catch for the extractor, an expandible gripper for 35 a single article on the extractor, a barrier within the chamber for the body of articles therein, an elevator for the articles, spring controlled means for raising the elevator, a lighter mounted adjacent the extractor, a single hand-operated control-device, separate means actuated by the hand-operated device to operate the lighter, positively close the gripper, interpose the barrier and release the extractor, and a spring acting on the released extractor to raise and partially extract 45 a cigarette and present it in an inclined position to be removed and with one end in position to be ignited by the lighter. 40

6. In a case for cigarettes and similar articles furnished with a chamber for a number of such articles, the combination of, an extractor, a pivot 50 for the extractor, at one side of the case, an expandible gripper for a single article on the extractor, means for opening the gripper, a barrier stop for the body of cigarettes in the chamber, 55 an elevator for said body of cigarettes, a spring acting on said elevator, a lighter mounted adjacent one end of the extractor, a single hand controlled device, separate means actuated by the hand controlled device to actuate the lighter, 60 positively close the gripper, interpose the barrier and release the extractor, a spring acting on the released extractor, to raise it and partially extract a cigarette and present it in an inclined position for removal and with one end in position to be ignited by the lighter, a lid on the lighter, 65 and means on the lid operative during the closing movement thereof to act upon and close the extractor. 70
